UNITED STATES PATENT OFFICE.

SPENCER HEATH, OF BALTIMORE, MARYLAND.

DESIGN FOR A HOLDER OR FRAME FOR CLOCKS, PICTURES, OR THE LIKE.

53,906.

Specification for Design.

Patented Oct. 7, 1919.

Application filed May 17, 1919. Serial No. 297,964. Term of patent 14 years.

To all whom it may concern:

Be it known that I, SPENCER HEATH, a citizen of the United States, residing at Baltimore, in the State of Maryland, have invented a new, original, and ornamental Design for a Holder or Frame for Clocks, Pictures or the like, of which the following is a specification, reference being had to the accompanying drawing, forming part thereof.

Figure 1 is a front elevation of the holder or frame, shown as used for a clock, al-

though a thermometer, barometer, picture, calendar or any other device may be substituted for the same;

Fig. 2 is a rear elevation of the same; and

Fig. 3 is a perspective view of the frame turned partly to one side.

I claim:

The ornamental design for a holder or frame for clocks, pictures or the like, as shown.

SPENCER HEATH.
